[57] CLAIM

The ornamental design for an etagere, as shown and
described.

DESCRIPTION

FIG. 1 is a front elevational view of an etagere showing
my new design;

FIG. 2 is a left side elevational view, the right side
elevational view being a mirror image thereof; and
FIG. 3 is a perspective view thereof.

The rear of the top canopy and bottom cabinet are flat
and unornamental.
